INSTRUMENT GRINDING DEVICE

Thomas J. Waldron, Allentown, N. J.

Application June 28, 1940, Serial No. 343,029

6 Claims. (Cl. 51—125)

The present invention relates to a device for grinding instruments and the like, and more particularly to a simple, inexpensive device to grind dental instruments.

An object of this invention is to provide an inexpensive means for sharpening dental tools wherein the tools can be bevelled at any desired angle.

Another object is to provide a clamp proportioned to fit a dental tray, table or the like, for holding the dental tool rigidly during sharpening.

Still a further object is to provide a portable, adjustable device for grinding dental tools and the like.

Another object is to provide a simple means for holding the dental tool steady relative to the sharpening stone.

Other and further objects and advantages of this invention will be apparent from the following description thereof and from the claims appended thereto.

In the drawing,

Figure 1 shows a top plan of the dental tool sharpening device attached to a tray and embodies the principal features of the invention.

Figure 2 shows a sectional view taken along the lines 2—2 of Figure 1.

Figure 3 shows a front elevation of the dental tool sharpening device attached to a tray.

Figure 4 shows an enlarged sectional detail of the ball and socket swivel joint which is adapted to receive the dental tool to be sharpened, and

Figure 5 shows an enlarged sectional detail of the dental hand piece carrying the sharpening stone.

Referring now to the drawing, the numeral 10 indicates generally a clamp adapted for firm attachment to a tray or table 11. Said clamp comprises a back portion 12 provided with two spaced apart ears 13 extending laterally therefrom. In the preferred form the ears 13 are provided with humped portions 13a adapted to snugly engage over the lip of a dental tray or the like.

Extending laterally from the lower end of the portion 12 and vertically spaced from ears 13, is a member 14 which is apertured at the outer end thereof to receive a threaded shaft 15 adapted to threadedly engage through said aperture and a downwardly projecting internally threaded bearing 16.

At the upper end of the shaft 15 is mounted a circular member 17 preferably provided on its upper surface with a cushioning layer of rubber

or the like 18 to engage the underside of tray 11.

Mounted on the lower end of the shaft 15 is a winged tip nut 19. Rotation of the nut 19 brings the cushioning layer 18 into closer position or further from the under side of the tray 11 to tighten or loosen the clamp 10 relatively to the tray 11.

On the side of the portion 12 oppositely disposed from the ears 13 and the member 14 of the clamp 10, is disposed means, generally indicated at 20, to clamp the dental hand piece 21 into a secure position.

The means 20 comprises a bar portion 22 extending substantially across the back of portion 12 in abutting relation therewith throughout its length except for the outwardly extending offset lug 23 which is proportioned to receive the dental hand piece 21.

The bar 22 at one end thereof is hingedly secured, as at 24, to a separate piece of metal or the like 25 which is anchored to the portion 12 by screws or the like 26. At its other end the bar 22 is recessed to receive a threaded shaft 27 mounted in the member 12 and extending outwardly therefrom. A winged-tip nut 28 threadedly engages said shaft 27 and rotation of the nut 28 in a clockwise direction securely fixes the bar 22 into abutting relation with the portion 12 to firmly hold the dental hand piece 21 in upright position within the lug 23.

In the preferred form of this invention there is a semicylindrical piece 29 mounted on the member 12 with its open end outward. Said piece 29 is of smaller diameter than lug 23 and fits therein when the bar 22 is locked into position to more securely hold the dental hand piece 21 upright.

The dental hand piece 21 is a standard piece of equipment used by dentists and per se forms no part of this invention. Mounted upon one end of the piece 21 is small wheel 21a recessed around its periphery to receive a belt, or the like, connected to a source of power, such as a motor.

The wheel 21a is keyed to a shaft 21b by a small bolt 21c extending through a nut 21d. The shaft 21b extends through and is supported by bearings 21e disposed in a casing 21f. Rotatably mounted on the other end of shaft 21d is a stone 21g, of the type used for sharpening dental tools. To insure against any vibration of the hand piece 21 during the sharpening operation, cotton or other cushioning material 21h may be packed around the piece 21 within the lug 23. The amount of material 21h used depends upon the

relative diameters of the lug 23 and member 29 compared with the diameter of piece 24.

A cylindrical hollow member or guide 30 is mounted on the portion 12, at one end thereof, and having the axis thereof substantially parallel to the axis of lug 23. The member 30 is proportioned to receive a rod 31 which is adapted to slide therein. The said member 30 is recessed intermediate the ends thereof to receive a nut 32 which threadedly engages therethrough to lock the rod 31 relatively to the member 30. The dental hand piece 21 and the slidable rod 31 are parallel and substantially in the same vertical plane when the clamp 10 is vertically fixed into sharpening or grinding position.

Mounted upon the upper end of the rod 31 is the dental instrument holding swivel means comprising two ears 33 proportioned to receive a swivel ball 34 and held in place by the screw 35 which firmly holds ears 33 against relative movement.

The swivel 34 has a hole 36 through its center of sufficient diameter to receive a dental tool 37. Extending at right angles from the hole 36 is another aperture which is internally threaded to engage a screw 38. The instrument 37 is locked into position by manipulation of the screw 38, which has its head substantially flush with the surface of the swivel ball 34 when the said screw 38 exerts pressure upon the tool 37, thus permitting the ball 34 to freely move in all directions.

In the operation of the invention, the dental instrument 37 is disposed in the hole 36 of the swivel ball 34 and locked into position by turning the screw 38. The screw 32 is unloosened to permit the rod 31 to freely slide in the member 30. If a long bevel is desired the rod 31 is lowered so that a greater surface of the point of the instrument 37 contacts the stone 21g. Once the desired bevel is ascertained the screw 32 is turned to lock the rod 31 in place.

The stone 21 is rotated, as by a motor, until the point of the instrument 37 which engages the said stone is sufficiently sharpened at the proper bevel.

The dental hand piece 21 is easily removable from the clamp 10 through hingedly attached bar 22 which is swung outwardly. This feature permits the easy substitution of dental hand pieces having stones of different abrasive or grinding characteristics.

The dental instrument 37 is easily removed after grinding by elevating it away from the stone 21g, relieving the pressure of screw 38 thereon, and withdrawing the said instrument from the ball and socket joint.

It is to be understood that the various parts of this invention may be constructed of materials such as iron, steel, plastics, or constructed in a modified form without departing from the spirit thereof.

It is therefore desired to be limited only by the scope of the appended claims.

What I claim and desire to secure by Letters Patent is:

1. A tool sharpening device comprising, a support for attachment to a tray or table, means carried by said support adapted to receive a sharpening stone, a cylindrical member carried by said support and spaced from said first mentioned means, a rod adapted to slidably engage

through said cylindrical member, means to lock said rod within said cylindrical member against relative movement, a ball and socket joint disposed at the upper end of said rod, said ball being centrally recessed to receive the tool to be sharpened, said ball being further recessed, and locking means engaging through said second recess to lock said tool in place.

2. In a tool sharpening device, means for holding the tool during the sharpening period comprising; a ball and socket joint disposed on a slid-
10 able member, a lock for said slidable member, said ball being centrally recessed to receive the tool to be sharpened, said ball being further recessed, and locking means engaging through said second recess to lock the tool in place during the sharpening period.

3. In a tool sharpening device, means for holding the tool during the sharpening period comprising; a ball and socket joint mounted on a slid-
20 able rod, a lock for said slidable rod, said ball being centrally recessed to receive the tool to be sharpened, said ball being further threadedly recessed at right angles to said first recess, and a screw to engage said threaded recess to lock the tool in place during the sharpening period.

4. In a tool sharpening device, means for holding the tool during the sharpening period comprising; a ball and socket joint disposed on a
30 slid-
able rod, a cylindrical guide for said rod, means to lock said rod relatively to said cylindrical guide, said ball being centrally recessed to receive the tool to be sharpened, said ball being further threadedly recessed at right angles to said first recess, and a screw to engage said threaded recess to lock the tool in place during the sharpening period.

5. In a tool sharpening device, means for holding the tool during the sharpening period comprising; supporting clamping means having two laterally extending arms in horizontally spaced relation and a third laterally extending arm vertically spaced from said first arms and provided with a recessed portion, adjustable means en-
40 gaging through said recessed portion adapted for adjustment relative to said horizontally spaced laterally extending arms, stone holding means pivotally secured to said clamping means oppo-
45 sitely disposed from said horizontally spaced lat-
erally extending arms, a cylindrical guide carried by said clamping means and spaced from said stone holding means, a rod adapted to slidably engage through said cylindrical guide, means to lock said rod within said cylindrical guide against relative movement, a ball and socket joint dis-
50 posed at the upper end of said rod, said ball being centrally recessed to receive the tool to be sharpened, said ball being further recessed, and locking means engaging through said second recess to lock said tool in place.

6. In a tool sharpening device, means for holding the tool during the sharpening period comprising; a ball and socket joint disposed on a slid-
60 able member, a lock for said slidable member, said ball being recessed to receive the tool to be sharpened, said ball being further recessed, locking means extending within said second recess, to engage said tool, and said locking means being disposed within the area limited by said second recess.

THOMAS J. WALDRON.
